UNITED STATES PATENT OFFICE.

ADAM DREKOLIAS, OF STATEN ISLAND, NEW YORK.

MEANS FOR PREVENTING THE SINKING OF SHIPS.

1,355,656.

Specification of Letters Patent.

Patented Oct. 12, 1920.

Application filed December 26, 1919. Serial No. 347,280.

To all whom it may concern:

Be it known that I, ADAM DREKOLIAS, a subject of the King of Greece, residing at Staten Island, in the county of Richmond and 5 State of New York, have invented certain new and useful Improvements in Means for Preventing the Sinking of Ships, of which the following is a specification.

This invention has relation to a ship, 10 and has for an object to provide a method and means for maintaining the same afloat at all times and to thus preserve the ship against sinking due to accident.

Another object of the invention is to 15 provide a method and means for preventing the sinking of ships which consists in placing a plurality of elements throughout the hold of a ship, said elements being manipulatable in such a manner as to offer buoyancy 20 to the ship, to prevent listing thereof or to otherwise change the center of gravity.

Another object of the invention is to provide means for preventing the sinking of ships which consists in providing a plurality 25 of expandable and collapsible floats of a specific construction which are located in any convenient location and any or all of which may be expanded or contracted to vary the volume thereof between minimum 30 and maximum limits and to keep the ship afloat in the event that its hull should become partly or completely flooded.

A still further object of the invention is to provide expandable and collapsible floats 35 for the purpose above set forth which are formed in various geometrical configurations for the purpose of accommodating themselves in various compartments of a ship's hold or for the purpose of grouping 40 them to secure variations of volume by their manipulation in a manner to be subsequently described.

A still further object of the invention is to provide a group of collapsible and expandable floats of my construction to be located 45 within tanks ordinarily employed for the purpose of storing water, fuel or the like whereby the float may be partly or wholly expanded, thereby occupying the space formerly occupied by the liquid to thus increase 50 the buoyancy of the ship.

In addition to the foregoing this invention comprehends improvements in the details of construction and arrangement of 55 parts to be hereinafter described and particularly set forth in the appended claims.

In the accompanying drawings in which similar and corresponding parts are designated by the same characters of reference throughout the several views in which they appear.

Figure 1. is a view in side elevation of a ship embodying my improvement.

Fig. 2. is a view in top plan of one of my collapsible and expandable floats. 65

Fig. 3. is a view thereof in side elevation.

Fig. 4. is a fragmentary view in section showing the joints between the parts of a float.

Fig. 5. is a plan view of a group of floats. 70

Fig. 6. is a plan view of a slightly different configuration.

Fig. 7. is a still further modified form of floats showing the same in top plan.

Fig. 8 is a top plan view of a still further 75 modified form of float.

Fig. 9. is a view in vertical section of a still further modified form of float employing a collapsible wall.

Fig. 10. is a horizontal section of the immediate preceding figure. 80

Fig. 11. is a view in top plan view of a group of circular floats.

Fig. 12. is a view in horizontal section taken on the line 12—12 of Fig. 13 illustrating the location of a group of floats in a ballast tank. 85

Fig. 13. is a view in vertical section taken on the line 13—13 of Fig. 12.

Fig. 14. is a view partly in perspective of 90 a modification of the invention, and

Fig. 15. is a still further modification of the form shown in the immediate preceding figure.

With reference to Figs. 2, 3 and 4, 10 indicates generally one of my collapsible and expandable floats, composed of a plurality of cups or casings, the uppermost of which is indicated at 11 and the lowermost at 12. In the present instance they are pyramidal in 95 configuration and are of different sizes so that one may fit within another, and each of which is provided with a top wall 13 so that they become inverted cups, the lowermost member 12 however is preferably entirely 100 inclosed. The members 11 and 12 and intermediate members are slightly frusto-conical somewhat after the manner of a collapsible drinking cup so that when the members are extended the large end of each member will 105 fit in the small end of the next to form a tight joint without the use of gaskets or

other packing means. The lowermost member 12 is provided with three radial arms 15, each of which has connected thereto a coil spring 16 having the upper ends of the 5 spring connected to members secured to a floor, ceiling or any other surface to which the float is to be attached. The function of the springs is to normally retain the floats in a collapsed condition. To extend the same I 10 provide a cable 17 which passes around a pulley and is connected at one end to the lowermost float 12 or preferably to an eye bolt secured in the center of the radial arm 15. I have indicated in Fig. 1, an outline 15 of a ship. The lower deck is indicated in dotted lines at 18. In the usual manner the hull of the vessel is divided into compartments 19 through the medium of bulkhead or partition walls 20. For the purposes of 20 my invention I provide a plurality of door openings 21 located in the hull of a vessel just below the lines of the lower deck 18 and normally closed by doors which, when open permit communication between the interior 25 and exterior of the vessel. A large number of expandible and collapsible floats, for instance of the types shown in Figs. 2, 3 and 4 are distributed throughout the interior of the vessel within the compartments 19 and 30 secured to the wall, ceiling, or other location, or stored beneath a bed, or other furniture so as to be normally unobstructive but which may be readily reached and manipulated when occasion requires.

35 In the operation of my invention in the event that the hull of the vessel is damaged at any point so as to permit the entrance of water, if only one compartment is flooded, and the usual bulkhead doors hold suffi- 40 ciently to prevent the entire hull from becoming flooded. The preservation of the vessel is a simple matter by the use of my invention. Thus, in the flooded compartment it is but necessary to extend or ex- 45 pand the float 10 to increase its volume to compensate for the loss in buoyancy which would normally have occurred due to the entrance of water into the compartment. It will thus be seen that listing or dipping 50 of the vessel as the result of the flooding of any compartment is entirely obviated for the reason that the buoyancy or uplifting effect of the expandible float is sufficient to offset the water displaced. In the event that 55 two or more compartments are flooded because of failure of the bulkheads to hold or because of extraordinary damage to the structure the entire vessel may be readily kept afloat by expanding a sufficient number of expandible floats 10 and suitably selecting the points where said floats are to be expanded so as to supply buoyancy to the vessel and to balance the same against listing or dipping. It will also be obvious that 60 65 if, in the event the ship is flooded through-

out its hold below the lower deck 18 all of the floats may be expanded throughout the entire hold, and to insure the quick balancing and righting of the vessel the doors 21 may all be opened so as to permit the entrance of sea water into the hold. This no doubt will have the effect of causing the vessel to settle somewhat but it will reach a point until the additional volume supplied by the floats 10 equals the amount of water 70 which has entered the hold and no further settling will take place as long as the floats are intact. It will also be apparent that in the event an opening occurs in the wall of the vessel at one side and the vessel should 75 list toward that side due to the entrance of water, the expansion of the floats within the flooded compartment will cause the vessel to rise somewhat upon the damaged side, but to effect a complete balancing or righting of 80 the vessel the doors 21 at the opposite side may be opened to permit the entrance of water into the compartment on that side until the vessel is righted. Thus, it will be seen that by suitably manipulating the 85 float and the doors 21 any vessel may be kept afloat or righted without any difficulty. I have illustrated in Fig. 5 an arrangement whereby four of the floats 10 may be grouped together, defining a rectangle when 90 viewed in plan. To effect an expansion of all of the floats 10 in unison I provide a plurality of radial arms 22 having springs 23 connected at their terminals, for the purpose of collapsing the float and having the 95 lowermost member 12 of each float connected to one of said arms 22 as shown. An additional volume is thus secured by the use of such a system of grouping which the 100 pyramidal form of the floats 10 readily permits. I have illustrated in Fig. 6 a form of float which is rectangular in plan as indicated at 24, the lowermost of which is provided with radial arms 25 having springs 26 connected to their terminals for the purpose of collapsing the floats. In Fig. 7 a 105 still further modified form of float is provided as indicated at 27, being oblong in configuration and having the lowermost member provided with a longitudinal ex- 110 tendsing central arm 28, to the terminals of which are integrally connected oppositely extending arms 29 for the purpose of attaching springs to their terminals in the manner previously described. In Fig. 8, I 115 have illustrated a still further modified form which, as indicated at 30 is circular in plan and which is provided with radial arms 31 secured to the lowermost member. To the terminals of said arms springs 32 are 120 connected. Each of the forms of floats just described is constructed in a manner identical with the pyramidal form and hence a further detail description thereof is not thought necessary. I have illustrated in 125 130

Fig. 9 a still further modified form in which 33 indicates the walls of a cabin, stateroom or the like and 34 the floor thereof. I provide a collapsible float illustrated at 35 and 5 comprising a plurality of circular disks which are covered by a casing 35^a of canvas, or other flexible material. The disks are normally held in contact near the ceiling by means of a coil spring 37 and may be lowered by means of a cable 36 attached to the lowermost member. When the disks are compressed the material of the casing 35^a folds between the disks and in this manner 10 a float occupying small space and which may be rendered ornamental is provided. When the float is expanded it will fill the interior of the cabin, etc., as shown in dotted lines. The disks are formed with central openings through which the spring 37 15 passes. I have illustrated in Fig. 11 a grouping of floats 30 of the type illustrated in Fig. 8. As will be seen I employ seven floats, arranged in circumferential order and provide a number of radial arms 38 to 20 the juncture of which the end member of the central float 30 is connected. The end members of the remaining floats are then connected to the arms 38, and coil springs are connected to the terminals of the arms 25 30 to collapse all of the floats in unison or to permit them to be expanded by means of a cable secured to an eye bolt 39 at the juncture of the arm.

I have illustrated in Figs. 12 and 13 a 35 different arrangement of floats and for this purpose I utilize the storage tanks 40 which are used in every vessel to hold water ballast, liquid, fuel or other material. For my purpose the tank must be air tight and 40 I secure to the under side of the top wall thereof a group of floats, preferably of the type shown in Fig. 7. The upper most member of each float in the group is secured to the under side of the top wall of the tank, 45 while the lowermost member of each float is connected to a frame consisting of longitudinal bars 42 and transverse bars 43 connected together. Coil springs 44 are connected to the terminals of the arms and to 50 the top wall 41 to retain the floats in a collapsed condition. To expand them I may employ a cable 45 passing around pulleys 46 located in the floor of the tank, said cable being subsequently led upward 55 through a pipe 47 within the tank and extending exteriorly beyond the top wall thereof, said cable subsequently passing over a pulley 48. I also employ an air pump, 60 preferably of the rotary type indicated at 49 and having outlet pipes 50 which extend into the tank through the top wall 41. I also employ a rotary pump 51 having an outlet 52 which is established in communication with the interior of the tank through 65 one vertical wall thereof.

Obviously, where sub tanks 40 are employed in the event that a ship becomes damaged and the hull partly flooded, the presence of any ballast, or fuel in such tanks would only tend to aggravate the condition, 70 and hence it is my object to relieve the tank partly or wholly of their contents and to establish a buoyant element therein which will be durable and withstand outward pressure in the event that the tank 40 should 75 leak or become damaged. To discharge the contents of the tank 40 the pump 49 is put into operation which will have the effect to discharge the contents thereof to a point corresponding to the lower end of the pipe 47 80 in the tank. To expel the liquid completely operation of the pump 49 is continued until all the liquid is forced out through the pipe 47 into the sea. The floats may now be expanded by applying strain upon the cable 85 45 which will extend the members of the group downward.

I also provide a plurality of emergency floats indicated at 55 in Fig. 1 and adapted to be expanded either vertically or horizontally and located upon and securely anchored to the upper deck. Thus, if by any reason the floats within the hold should fail the emergency floats 55 will retain the ship 90 upon the surface of the water and thus prevent its complete loss.

If the masts 56 are of the hollow steel type I propose to install a float in each one so that this space may also be utilized to 100 accord buoyancy to the vessel.

I have illustrated in Figs. 14 and 15 the lower end of a smoke stack 57 which, in the case of Fig. 14 is closed at its lower end by means of a hingedly mounted door 58 which is normally open but adapted to be 105 tightly closed in an emergency to thus render the smoke stack available as a float to add to the buoyancy of the vessel. The same idea is carried out in Fig. 15 in which two semi-circular doors 59 are employed, one of 110 which is shown in closed position and the other in open position, a fragment only of the latter being shown, thus providing another form of closure.

An advantage of the use of this system is 115 that it is especially adapted for use in extinguishing fires in the hold of a vessel, thus, should a fire occur in one or more compartments it is but necessary to flood the compartment entirely with water by opening 120 the doors 21 or any other means of communication, and at the same time expanding a number of floats within said compartment sufficiently to maintain the buoyancy of the vessel. An additional means of extinguishing fires may be also provided by filling one or more of the lower members 12 of any of the floats with carbon-dioxid gas under 125 compression, with suitable valves so that the gas may be released when necessary. 130

From the foregoing it will be seen that I have provided a system whereby the maintenance afloat of any vessel may be absolutely insured, and whereby the perfect balancing, either laterally or longitudinally may be absolutely accomplished without difficulty.

While I have illustrated and described my invention with some degree of particularity, 10 I realize that in practice various alterations therein may be made. I therefore reserve the right and privilege of changing the form of the details of construction without departing from the spirit of the invention 15 or the scope of the appended claims.

Having thus described my invention, what I claim as new and desire to secure what is described by United States Letters Patent is:—

20 1. In combination with a vessel having its interior divided into a plurality of watertight compartments, means for establishing communication between the interior and exterior of each compartment, and a plurality 25 of displacement devices located in each compartment with means for expanding or collapsing them to maintain the buoyancy and balance of the vessel.

2. In combination with a vessel, a plurality 30 of displacement devices located therein, each device having one end secured to a stationary portion of the vessel, resilient means for normally retaining the device in a collapsed condition, and means for connection to the opposite end of the device to expand the same.

3. A displacement device including a plurality 35 of inverted cup members of different diameters arranged to inclose one within another, resilient means tending to normally collapse the arrangement, and means for extending the device by pulling one cup from within the other.

4. A displacement device including a plu-

rality of pyramidal cup members of different perimeters, so as to receive one within another, means for retaining the system normally collapsed, and means for expanding the system by withdrawing one member from another.

5. A displacement device including a plurality of groups of individual displacement devices, each device including a plurality of members for interfitting engagement one with another, means for expanding all of 55 the devices of a group simultaneously, and resilient means tending to normally retain all of said devices of the groups collapsed.

6. A displacement device comprising four groups of individual displacement devices, 60 each group consisting of triangular cup members of different perimeters one within another, the arrangement of the individual devices defining a rectangle, resilient means tending to collapse all of the displacement 65 devices of the groups simultaneously, and means connected in common to one member of each device for expanding all of the devices simultaneously.

7. In combination, a tank, a group of individual displacement devices secured to the top wall thereof interiorly of the tank, each individual device comprising a plurality of inverted cups of different sizes arranged in telescopic relation, and means for connecting the lowermost cups of each group, a cable connected to said means for withdrawing the lowermost cup simultaneously to expand the arrangement as a whole, and means for withdrawing the contents of the 80 tank.

In testimony whereof I affix my signature in presence of two witnesses.

ADAM DREKOLIAS.
